UNITED STATES PATENT OFFICE.

FRANK H. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

TRIMMING MACHINE.

Application filed September 29, 1920. Serial No. 413,464.

To all whom it may concern:

Be it known that I, FRANK H. WARREN, a citizen of the United States, residing at Swampscott, in the county of Essex and 5 State of Massachusetts, have invented certain new and useful Improvements in Trimming Machines; and I do hereby declare the following to be a full, clear, and exact description of the invention, such as will enable others skilled in the art to which it 10 appertains to make and use the same.

The present invention relates to trimming machines for use in the manufacture of boots and shoes, and has special reference to 15 such machines for trimming the projecting edges of the vamp and lining of a lasted shoe preliminary to the inseam sewing operation.

Commercial machines of this type are 20 usually provided with a reciprocating trimming knife that works across a shearing face at one end of a guide roll, the other end of the guide roll being arranged to engage the sole of the shoe to act as a distance gage to 25 determine the height of the trimming cut. The guide roll is driven and its peripheral surface is frusto-conical and knurled so that it may act to feed and guide the work and to turn up the portions of the edges of the 30 vamp and lining that project inwardly from the line of lasting to present such portions to the trimming knives. With the use of this guide roll, however, it is necessary for the operator to exercise a high degree of 35 care in order to guide and feed the work properly and, also, because of the width of the roll and the restricted area at the toe of a pointed toe shoe, the guide roll is unable, in many cases, to act properly on this portion 40 of the edges of the vamp and lining.

Various guiding devices have also been proposed for these machines for turning up the portions of the edges of the vamp and lining that project outwardly from the line 45 of lasting to present these portions to the trimming knives, but the devices heretofore proposed for this purpose have not proved entirely satisfactory on certain classes of work. One of these prior devices comprises 50 a plow shaped member formed on the forward end of a forwardly spring pressed sliding carrier and arranged to press against the work in advance of the trimming knives.

One objection to this device is that as the shoe is turned in trimming about the toe of 55 a pointed toe shoe, there is danger of the edges of the vamp and lining being brought away from the plow so that the plow cannot act effectively on them at this point.

The principal object of the present invention is to provide an improved machine for trimming the projecting edges of the 60 vamp and lining of a lasted shoe preliminary to the inseam sewing operation, which overcomes the disadvantages above described of 65 the prior constructions while retaining all of the advantages.

With this object in view, a feature of the present invention comprises the provision, in a trimming machine having means for 70 trimming the projecting edges of the vamp and lining of a lasted shoe, of a member adapted to rock so as to follow the contour of the shoe in advance of the trimming means for presenting the outwardly projecting edges of the vamp and lining to the trimming means. This feature of the invention is particularly advantageous in 75 trimming the toe of a pointed-toe shoe, as the rocking of said member enables it to 80 maintain better control of the vamp and lining in advance of the trimming means while the heel of the shoe is being swung about the trimming means. Preferably, 85 said member is plow shaped, and in order that it may keep such control of the vamp and lining it is preferably pivotally mounted between its ends on the forward end of a work-guiding device which is yieldingly urged against the edge of the shoe, although 90 this specific construction is not essential to the broader features of the invention.

Another feature of the present invention comprises the provision, in a trimming machine of novel means for guiding and trimming the projecting edges of the vamp and lining of a lasted shoe, said means comprising a trimming member having a portion 95 constructed to act as a channel guide to guide the work and also having a portion 100 to act on the projecting edges of the vamp and lining to present them to the trimming means. It will be apparent that the operation of said member in this manner enables the operator to guide and feed the work 105 without difficulty. In the construction illus-

trated in the drawings of this application, said member comprises a frusto-conical guide roll having its larger end provided with a shearing face across which a reciprocating trimming knife works and having a head or button formed on its smaller end to engage the root of the channel on the sole, a groove adapted to receive the channel flap being provided by the head, neck and body 10 of the roll. It will be apparent that the small diameter of the neck enables the large or over-hanging body portion of the roll to engage and act on the portion of the vamp and lining at the tip of a pointed-toe shoe. 15 Other features of the invention consist in certain constructions, arrangements, and combinations of parts hereinafter described and claimed, the advantages of which will be obvious to those skilled in the art. 20 The several features of the invention will be clearly understood from the following description and accompanying drawings, in which:

Figure 1 is a left side elevation of a portion of the head of a trimming machine embodying the features in their preferred form; Fig. 2 is a sectional plan view taken on a line just above the frusto-conical guide roll; Fig. 3 is a front view of a portion of the machine illustrated in Fig. 1; and Fig. 4 is a side elevation partly in section of the guide roll and its supporting means.

The illustrated machine is provided with a reciprocating trimming knife 2 that works 25 across a shearing face 4 at the upper end of a guide roll 6 which is secured to the lower end of a driven shaft 8. The machine is also provided with a work guiding device 30 comprising a plate which is mounted to slide in a dove-tail way on a bracket 12 secured to the frame of the machine. The work guiding device is urged forwardly toward the work by means of a spring 14 having one end secured to the bracket 12 and its 35 other end engaging the rear end of the work guiding device, the forward movement of the device being limited by a screw 16 extending through a slot in the bracket 12 and screw 40 threaded into an aperture in the work guiding device plate. The parts above described 45 are substantially the same in construction and mode of operation, except as hereinafter described, as the corresponding parts of the machine illustrated and described in the application of Moses E. Shackley, Serial No. 50 306,912, filed June 26, 1919.

In the illustrated machine, instead of the guide roll being screw threaded on a stud 55 projecting from the end of its driving shaft as has heretofore been customary, it is formed with a screw shank 18 which screws into a bored and tapped socket in the end of the shaft 8, resulting in the roll being more rigidly mounted and stronger than 60 in the prior constructions.

The guide roll in the illustrated machine is provided with a head or button 20 and a neck 22 of relatively small diameter at the lower end of the body portion, a groove being thereby formed between the button and the body portion of the roll to receive the channel-flap. The button is designed to engage the root of the channel, and thus act as a channel guide for the work. The peripheral surface of the body portion of the 70 guide roll is frusto-conical and is spirally knurled so that the roll may lift the projecting edges of the vamp and lining to present them to the trimming knives. The 75 relatively small diameter of the neck portion 80 of the roll enables the body portion to overhang the channel-flap so as to extend closer to the tip of the toe than is possible with the usual frusto-conical roll and to maintain better control of this portion of the 85 projecting edges of the vamp and lining to present them to the trimming knives.

It will thus be seen that the roll 6 acts as a combined height gage to determine the height of the trimming cut, a channel guide, 90 and a guide for the projecting edges of the vamp and lining.

Instead of a non-oscillatory plow formed on the forward end of the work guiding device 10, as in the machine of said co-pending application, the illustrated machine is provided with a plow 24 which is pivotally mounted between its ends on the forward end of the work guiding device. The plow comprises a block adapted to turn freely 100 on a vertical stud or pin 26 on the end of an arm 28 extending laterally from the work guiding device and provided with a forwardly projecting end 29. The under side of the block 24 is provided with a recess 105 30 to receive the end of the arm 28, the two parts embodying a mortise construction and the pivotal movement of the plow being limited by the engagement of the side walls of the recess 30 with the sides of the end 110 of the arm. The block 24 is held on the arm 28 by means of a plate 32 secured to the under side of the block and extending across the under side of the end of the arm 28. 115

In Fig. 2 a central or intermediate position of the plow is shown by full lines, and the extreme rearward and forward positions of the plow are shown by broken lines. It will be apparent that in trimming the projecting edges of the vamp and lining at the shank and the sides of the forepart of the shoe that the plow will assume substantially the position shown in full lines in Fig. 2, and that as the shoe is turned about the guide roll 125 in trimming the toe portion of the projecting edges, the pressure of the work which is at this time concentrated at the trailing end of the plow will swing the leading end toward the untrimmed side of the shoe so as to ad- 130

vance the point of initial control. The illustrated construction has the additional advantage of affording temporarily an abutment 11 to engage the toe end of the shoe 5 so as to retard the feed past the field of trimming while the heel end is being swung to reverse the shoe end for end. This abutment is a rounded hump formed on the carrier 10. In conjunction with the trailing 10 end of the follower 24 it forms a recess into which the toe settles during the swinging of the heel, but from which the toe glides gradually as the heel is about to complete its swinging. The abutment does not project 15 so far as the follower, and consequently remains out of contact with the shoe excepting at the toe end. Furthermore, since a sharp toe will enter the recess to a greater extent than a blunt toe it will be retarded to 20 a correspondingly greater extent by the abutment, and in this respect the device automatically controls the speed of feeding the toe past the field of trimming so that the more difficult toes will move less rapidly.

25 While it is preferred to employ the specific construction and arrangement of parts illustrated and described, it is to be understood that this construction and arrangement is not essential except so far as specified in the 30 claims, and may be changed or modified without departing from the broader features of the invention.

The nature and scope of the present invention having been indicated and a machine 35 embodying the several features of the invention in their preferred form having been specifically described, what is claimed is:—

1. A trimming machine for use in the manufacture of boots and shoes having, in 40 combination, means for trimming the projecting edge of the vamp of a lasted shoe, and work-guiding means comprising a carrier and a follower carried by and pivotally connected to said carrier, said follower being 45 formed and arranged to bear on the outer surface of the material to be trimmed, so as to guide said material to said trimming means and so as to be rocked to various positions in the contour of said 50 material, and a spring arranged to urge said carrier toward the work.

2. A trimming machine for use in the manufacture of boots and shoes having, in combination, means for trimming the projecting edge of the vamp of a lasted shoe and 55 working-guiding means comprising two abutments in tandem relation the leading one of which is formed and arranged to bear on the outer side of the material to be trimmed, so as to guide said material to the trimming means, said abutments being separated to provide a space to receive the toe end of the shoe as the latter is turned, the other one of said abutments being arranged to engage the toe end

but to clear the shoe when the sides of the latter are running on said leading abutment.

3. A trimming machine for use in the manufacture of boots and shoes having, in 70 combination, means for trimming the projecting edge of the vamp of a lasted shoe, and a pivoted follower formed and arranged to bear continuously on the outer surface of the material to be trimmed, so as to guide said 75 material to said trimming means and so as to be rocked to various positions by variations in the contour of said material.

4. A trimming machine for use in the manufacture of boots and shoes having, in 80 combination, means for trimming the projecting edge of the vamp of a lasted shoe, and work-guiding means comprising a member movable bodily toward and from the shoe and having a shoulder formed and arranged to engage the toe end as the shoe is turned, a follower carried by and pivoted to said member and arranged to engage the material to be trimmed, so as to guide said material to the trimming means, and a 85 spring arranged to urge said bodily movable member toward the work.

5. A trimming machine for use in the manufacture of boots and shoes having, in combination, means for trimming the projecting edge of the vamp of a lasted shoe, and means for presenting the projecting edge of the vamp to the trimming means as the shoe is fed past the trimming means 95 comprising a member pivotally movable to 100 enable it to adjust itself to the contour of the shoe, and means for bodily urging said member toward the shoe.

6. A trimming machine for use in the manufacture of boots and shoes having, in 105 combination, means for trimming the projecting edge of the vamp of a lasted shoe, a member adapted to adjust itself to the contour of the shoe in advance of said trimming means to present the projecting edge of the 110 vamp to the trimming means, and means comprising a sliding carrier for said member for bodily urging the member toward the shoe.

7. A trimming machine for use in the 115 manufacture of boots and shoes having, in combination, means for trimming the projecting edge of the vamp of a lasted shoe, and pivoted means arranged to engage the projecting edge of the vamp so as to present 120 it to the trimming means, said pivoted means being angularly movable by the vamp and otherwise movable to maintain contact with the work.

8. A trimming machine for use in the 125 manufacture of boots and shoes having, in combination, means for trimming the projecting edge of the vamp of a lasted shoe, a work guide engaging the shoe opposite the trimming means, and a member constructed 130

- and arranged to present the projecting edge of the vamp to the trimming means and to have a compound movement such as to enable it to follow the contour of the shoe.
5. 9. A trimming machine for use in the manufacture of boots and shoes having, in combination, means for trimming the projecting edge of the vamp of a lasted shoe, a work guiding device movable in a plane substantially parallel to the sole, and a member pivotally mounted on the work-guiding device adapted to adjust itself to the contour of the shoe for presenting the projecting edge of the vamp to said trimming means.
10. 10. A trimming machine for use in the manufacture of boots and shoes having, in combination, means for trimming the projecting edge of the vamp of a lasted shoe, and means arranged to engage the projecting edge of the vamp so as to present the latter to said trimming means and comprising a member pivoted between the ends of its work-engaging face to enable the work to rock it in opposite directions.
15. 11. A trimming machine for use in the manufacture of boots and shoes having, in combination, means for guiding and trimming the projecting edge of the vamp of a lasted shoe comprising a roll having a shearing face at one end and a guiding member at the other end arranged to engage the root of the channel of the sole, and a trimming knife working across said shearing face.
20. 12. A trimming machine for use in the manufacture of boots and shoes having means for guiding and trimming the projecting edge of the vamp comprising a roll having a shearing face and a flange formed and arranged to engage the root of the channel of the sole, and a trimming knife working across said shearing face.
25. 13. An upper-trimming machine comprising trimming means, means arranged to guide the shoe relatively to said trimming means by engagement with the channel of the sole, and means arranged to guide the surplus upper material to the field of trimming and keep the channel-flap out of said field.
30. 14. An upper-trimming machine comprising trimming means, a channel guide, and means arranged to separate the surplus upper material from the channel-flap so as to guide the former into the field of trimming.
35. 15. An upper-trimming machine comprising trimming means, a channel guide, means arranged to limit the bending moment of the channel-flap as raised by said channel guide, and means arranged to bend the sur-
- plus upper material away from the channel-flap so as to guide it into the field of trimming.
40. 16. An upper-trimming machine comprising trimming means including a shearing roll having a channel-guiding portion and a portion arranged to separate the surplus upper material from the channel-flap so as to guide the one into and keep the other out of the field of trimming.
45. 17. An upper-trimming machine comprising cooperative shearing members one of which is a roll arranged to engage the inner side of the material to be trimmed, said roll having a head formed and arranged to enter the channel of the sole, and having a neck of relatively small diameter connecting said head with the shearing portion, said head, neck and shearing portion forming a groove to receive the channel flap of the sole.
50. 18. A trimming machine for use in the manufacture of boots and shoes having, in combination, a rotating shaft, a guide roll having a shearing face at one end and having its other end of relatively small diameter and directed toward the surface of the sole of a shoe placed in the machine to determine the distance from the surface of the sole at which the vamp should be trimmed, a stud formed integral with the roll and screw-threaded into an aperture in the end of said shaft, and a trimming knife working across said shearing face.
55. 19. An upper-trimming machine comprising trimming means including a trimming member formed and arranged to engage the sole in the channel, to guide the surplus upper material to the field of trimming, to determine the closeness of trimming, and to keep the channel-flap out of the field of trimming.
60. 20. An upper-trimming machine comprising cooperative trimming members one of which is a driven roll having a knurled portion for acting on the material to be trimmed, and having a smooth head, and a neck of relatively small diameter connecting said head with said knurled portion, said head being formed and arranged to act as a channel guide and said neck providing a groove to receive the channel-flap of the sole.
65. 21. An upper-trimming machine comprising a trimming member, and a work-guide formed and arranged to straddle the channel-flap of the sole so as to guide the work partly by engagement with the channel and partly by engagement with the surplus upper material.

FRANK H. WARREN.
